FISHING LURE OR SIMILAR ARTICLE

Roy A. Lord, Evanston, Ill.

Application September 24, 1953, Serial No. 26,943

Term of patent 14 years

(Cl. D31—4)

To all whom it may concern:

Be it known that I, Roy A. Lord, a citizen of the United States of America, residing at 2625 Hurd Avenue, Evanston, State of Illinois, have invented a new, original, and ornamental Design for Fishing Lure or Similar Article, of which the following is a specification, reference being had to the accompanying drawings forming a part hereof.

Fig. 1 is a perspective view of a fishing lure, showing my new design.

Fig. 2 is a perspective view showing the other side of the fishing lure shown in Fig. 1.

Fig. 3 is a top perspective view of the lure.

Fig. 4 is a bottom perspective view of the lure.

Fig. 5 is a front elevation view of the lure.

Fig. 6 is a cross-sectional view taken on line 6—6 of Fig. 1.

I claim:

The ornamental design for a fishing lure or similar article, substantially as shown.

ROY A. LORD.
